CLAIM

The ornamental design for a dispenser, as shown and described.

DESCRIPTION

FIG. 1 is a top, front, right perspective view of a dispenser showing the claimed design;

FIG. 2 is a front view thereof; and,

FIG. 3 is a right side view thereof, wherein the left side is a mirror image of FIG. 3 and is claimed.

The dashed broken lines in the drawings show portions of the dispenser that form no part of the claimed design.

The dot-dash broken lines in the drawings represent the bounds of the claim and form no part of the claimed design.

The shade lines in the figures show contour and not surface ornamentation.
